UNITED STATES PATENT OFFICE.

JAMES F. McLAUGHLIN, OF PHILADELPHIA, PENNSYLVANIA.

TELEPHONIC APPARATUS.

SPECIFICATION forming part of Letters Patent No. 355,189, dated December 28, 1886.

Application filed May 29, 1886. Serial No. 203,601. (No model.)

To all whom it may concern:

Be it known that I, JAMES F. McLAUGHLIN, a citizen of the United States, and a resident of Philadelphia, in the county of Philadelphia and State of Pennsylvania, have invented certain new and useful Improvements in Telephonic Apparatus, of which the following is a specification.

The object of my invention is to effect an improvement on my previous Patent No. 328,702, dated October 20, 1885, for the transmission of intelligence by vocal sounds, sign, or speech by magnetic or electric impulses, whereby the sounds are increased in volume and intensity and greatly amplified.

In carrying out my invention the well-known magneto-electric machine may be used, or any suitable machine for generating electricity.

20 The main features of my invention consist of enlarged metallic diaphragms or disks enclosed by suitable air-chambers, which concentrate at a certain point, either at the receiver or transmitter, and in the peculiar arrangement of the field-magnet, together with minor parts, which will be hereinafter more particularly described, and pointed out in the claims.

30 The drawing represents a sectional view of appliances embodying my invention.

In the drawing, A represents the box, of any desired form or material.

35 a' a'' are thin disks of metal, (preferably iron,) which are secured at the two opposite ends of the box A.

B is an electric bell, secured in any suitable manner in the box, as is also a magneto-electric machine, C.

40 G is a round flexible tube attached to the air-chamber E', and on one end of which is secured the mouth-piece g.

c' c'' are the poles of the field-magnet and generator C.

45 c''' c'''' are extensions, which may be separated or secured to the poles in any suitable manner.

E E' represent air-chambers attached to the sides of the box for the purpose of amplifying or confining the sound.

50 The generating-machine may be of any suitable or desired construction, and disposed or located as circumstances dictate. The exten-

sions c''' c'''' are brought to within a short distance of the inner sides of the ends of the box, as shown in the drawing, and around them and the whole length of the magnets of the generator is wrapped a layer or coil of wire for the purpose of intensifying the magnetic and electric effect produced by the vibration of the ends of the box. One end of this wire is connected to line through binding-post X, and the other through binding-post Z. Such construction provides a dynamo or magneto-electric machine, the field-magnets of which are wrapped with an extension of the line-wire 65 connected to the ground-wire. The thin vibratory ends of the inclosing-box, the air-chamber, and the aural tube are for the purpose of confining and amplifying any sounds or signals the apparatus may transmit or receive. 70

From the foregoing it is apparent that whenever a call is made or the armature of the generator is rotated, the magnetism of the field-magnets is re-enforced. It will also be seen that the means for automatically maintaining 75 the efficiency of the apparatus and transmitting device is contained within the apparatus itself.

If from continued disuse the sounds reproduced are indistinct or weak, the maximum 80 efficiency can instantly be regained by a rotation of the armature.

I would here state that I do not confine myself to the use of an aural tube to only one end of the air-chamber, as either end may be used 85 to transmit or receive sounds or signs, according to the option of the user. Neither do I wish to confine myself to the use of the extension-pieces of the field-magnets, as the apparatus will perform its work without such extension-pieces. 90

Having thus described the nature, operation, and advantages of my invention, what I claim, and desire to secure by Letters Patent, is—

1. In combination with the box A, made 95 without ends, the magnetic diaphragm a' a'', secured to the said box and forming the ends thereof, and the tapering air-chambers E E', terminating in the ear or speaking tubes, as set forth.

2. In combination, the box A, the magnetic diaphragms a' a'', forming the ends thereof, the magnet having extensions c''' c'''' ending near the diaphragms, and the line-wire coiled 100

around the magnet and its extensions, as set forth.

3. In combination, the box having magnetic diaphragms $a' a''$, forming its ends, the air-chambers tapering to their centers, and the generator having the line-wire coiled around the full length of its magnet, as set forth.

4. In a telephone-receiver, the combination, with a magneto-generator, of two magnetic diaphragms, one in proximity to each of the poles thereof, the coils of the said generator

being wound along the whole body of the magnet and being also connected to the line-wire, as and for the purpose set forth.

Signed at Philadelphia, in the county of 15 Philadelphia, and State of Pennsylvania, this 21st day of May, A. D. 1886.

JAMES F. McLAUGHLIN.
